UNITED STATES PATENT OFFICE.

THOMAS B. WYLIE, OF OSBORNE, PENNSYLVANIA.

METER-REGULATOR.

No. 888,952.

Specification of Letters Patent.

Patented May 26, 1908.

Application filed June 15, 1907. Serial No. 379,162.

To all whom it may concern:

Be it known that I, THOMAS B. WYLIE, of Osborne, Allegheny county, Pennsylvania, have invented a new and useful Improvement in Meter-Regulators, of which the following is a full, clear, and exact description, reference being had to the accompanying drawings, forming part of this specification, in which—

10 Figure 1 is a top plan view of the meter provided with my improved regulator, the top being removed; Fig. 2 is a sectional side elevation of the same; Fig. 3 is a cross sectional view on the line III—III of Fig. 2, and Fig. 4 is a view similar to Fig. 2 but at right angles thereto; Figs. 5 and 6 are views of a modified form.

20 My invention relates to meters for gaseous fluids and especially to dry gas meters controlling the flow of gas to burners.

When gas meters are employed in buildings, it is desirable that the pressure at the burner should remain constant. Where a reducing valve is used at or near the inlet to the meter, the pressure at the burners does not remain constant since the friction loss in pressure in the meter increases as the volume increases. Consequently with increasing volumes the burner pressure becomes lowered below the proper amount with such constructions. This difficulty can be overcome by placing the reducing valve on the outlet from the gas meter. Such a structure would give a substantially constant pressure to the 35 burner but is open to the serious objection of giving high pressure within the meter.

My invention is designed to overcome this difficulty while giving a low pressure in the meter; and consists in providing a pressure 40 device which is acted upon by the gas leaving the meter, this pressure device being connected to a valve or controlling apparatus for the gas entering the meter. In this manner any variation in the pressure absorbed 45 in the meter will be compensated for, since if the pressure starts to drop at the outlet, the pressure device at the outlet will open the inlet valve to give more volume and pressure.

50 In the drawings, I show the invention as applied to a dry gas meter of the type set forth in my co-pending application, Serial No. 340,331, filed October 24th, 1906, for dry gas meter. It will, however, be under-

stood that the system may be applied to any 55 gas meter and may be varied widely in form and arrangement.

In the drawings, 2 represents the general case of the meter, having an upper transverse partition 3 on which is mounted the 60 valve box 4, the bottom 5 of which forms the valve table. The inlet pipe 6 leads into the top of this valve case and into the elbow fixture 7, the outlet port 8 of which opens into the valve box and is controlled by valve 65 9 mounted on the curved rock arm 10 secured to rock shaft 11, (Fig. 5). This shaft is mounted in a suitable bearing 12 combined with the stuffing box 13 secured around a hole through the valve box through 70 which the rock shaft extends. To the outer portion of the rock shaft 11 is secured the lever 14 which is pivoted at its other end to the hub 15 of a diaphragm plate 16 to which is secured one edge of the flexible diaphragm 75 17. The upper edge of this diaphragm is secured to the diaphragm chamber 18 from the top of which a small tube 19 leads through the top 20 of the meter chamber. This provides for atmospheric pressure on the one 80 side of the diaphragm.

The gas which has been measured in the meter flows into the chamber 21 containing the diaphragm device and subjects the diaphragm plate to its pressure as it flows to the 85 outlet 22 from the meter. It will therefore be clear that any variation in pressure of the gas flowing from the meter will shift the valve 9 controlling the flow of gas into the meter. A substantially constant pressure 90 will therefore be preserved in the gas passing from the meter to the burners or other point of use.

In the form shown, 23 and 24 are D-valves 95 operating on the valve table and connected to links 25 and 26. These links are secured to cranks on the vertical shaft 27 which extends through a stuffing box in the top of the valve box and is provided above the valve box with a crank driven by links 28 and 29 connected to the cranks 30 and 31. One valve controls three ports leading from the valve table, of which the two outer ports are inlet and the intermediate ports are exhaust ports for the gas. The two outer supply and exhaust ports lead into the diaphragm chambers shown at 32 and 33 of which two are 100 preferably employed for each D-valve.

These diaphragms may be operated in the usual manner and form no part of my present invention.

Instead of building the meter with the regulator device as a part thereof, I may construct the regulator as a separate attachment which can be applied to any desirable form of meter. Thus, in Figs. 5 and 6, I show a meter 34 having an inlet pipe 35 and an outlet pipe 36. To the pipes 35 and 36 are secured by suitable pipe unions or couplings, a gas box having a large chamber 37 and a smaller chamber 38 separated by the partition wall 39. The gas enters 15 the chamber 38 through pipe 40 and is controlled by the valve 41 secured to rock shaft 42. This rock shaft is mounted in suitable bearings, and at one side extends through a stuffing box 42' secured to the 20 wall 39. To the protruding end of this shaft is secured a curved lever arm 43, the other end of which is pivoted to the diaphragm plate 44 of a diaphragm chamber 45 in the outlet gas chamber 37. The gas passing 25 out through pipe 36 enters the chamber 37, and thence passes to the second outlet pipe 46. In this case as before, the pressure of the outgoing gas acting on the diaphragm controls the position of the throttling inlet 30 valve. This form may be attached to existing meters.

The advantages of my invention will be apparent to those skilled in the art, since the desirable uniform pressure beyond the meter 35 is obtained without the use of high pressure in the meter.

The invention may be applied to any type of meter or measuring device for gaseous fluids and the regulating apparatus may be 40 widely varied without departing from my invention; since I consider myself the first

to provide a meter with an inlet valve which is controlled by the pressure of the outgoing fluid.

I claim:—

1. The combination with a meter, of an inlet valve therefor and a pressure device controlled by the out-going fluid and connected to said valve, the pressure device being open to the atmosphere on one side thereof; substantially as described. 45

2. A dry gas meter having an inlet valve controlling the flow into the meter, a diaphragm pressure device subjected to the pressure of the out-going fluid on one side 55 thereof and to atmospheric pressure on the other side and a connection between the movable member of the pressure device and the inlet valve; substantially as described.

3. A meter having an inlet control valve, 60 a chamber subjected to the pressure of the gas flowing from the meter, a pressure device in said chamber open to atmospheric pressure on one side thereof and a connection extending between the pressure device and the 65 inlet valve; substantially as described.

4. A gas meter having an inlet control valve, a chamber subjected to the pressure of the out-flowing fluid, a pressure device in said chamber and open to atmospheric pressure on one side thereof, a stuffing box between the outflowing fluid chamber and the inlet control valve, and a mechanical connection extending through the stuffing box or sealing device from the pressure device to the 70 inlet valve, substantially as described. 75

In testimony whereof, I have hereunto set my hand.

THOMAS B. WYLIE.
